UNITED STATES PATENT OFFICE

JOHN HENRY JUERS, OF PASSAIC, NEW JERSEY, ASSIGNOR TO TRIPLEX SAFETY GLASS COMPANY OF NORTH AMERICA, OF NEW YORK, N. Y., A CORPORATION OF DELAWARE

APPARATUS FOR SPRAYING GLASS, ETC.

Application filed July 25, 1929. Serial No. 380,898.

This invention has been developed with particular reference to the spraying of glass preliminary to its assemblage with a sheet of celluloid or similar material in the manufacture of what is known as laminated or non-shatterable glass. In such manufacture the glass or the celluloid or both is or are commonly sprayed with a solution which promotes the adhesion of the glass and celluloid. 5 After the preparation of the glass and the celluloid, the two sheets of glass and the interposed sheet of celluloid are assembled under heat and pressure. It has been found necessary, in order to accomplish satisfactory results, that the solution be applied with as nearly perfect uniformity as it is possible to attain. The liquid is supplied under pressure from a suitable source through a spray head which is reciprocated transversely over the glass or material to be coated while the latter is moved longitudinally at a uniform rate. It has been attempted to effect the delivery of the solution through a spray head which is oscillated in the arc of a circle 15 by means of a crank and pitman, but it has been found that with such means the spray coat is relatively heavy at and near the edges of the glass and relatively thin in the middle. It is the object of this invention to provide 20 an apparatus by which the spray head shall be supported and reciprocated in such manner as to effect substantially uniform distribution of the solution over all parts of the glass as the glass is moved forward at a uniform rate, 25 and it has been found that this object can be accomplished under the conditions of operation by causing the spray head to move on the chord of the arc rather than on the arc itself. 30 The invention will be more fully explained hereinafter with reference to the accompanying drawings in which it is illustrated as embodied in a suitable form of mechanism, and 35 in which:

Figure 1 is a view in front elevation of the spray distributing mechanism, a portion of the means for producing the longitudinal movement of the glass being indicated, partly 40 in section.

Figure 2 is a view of the same in side elevation.

Figure 3 is a view of the same as seen from above.

Figure 4 is a detail view partly in section and on a larger scale.

The spray head *a* may be of any usual or suitable construction. A well known form is shown in the drawings and is represented as being connected through a flexible pipe *a*¹ 60 with the source of liquid to be sprayed, through a similar flexible pipe *a*² with a source of air under pressure, and through a similar flexible pipe *a*³ with a source of air under more moderate pressure. The spray 65 head is pivotally supported by a holder *b* which is arranged to slide on slide rods *c* supported by the frame *d*. The movement of the spray head is effected most conveniently by a crank, indicated at *f*, and operated from 70 a motor *f*¹ through suitable reducing gears indicated at *f*². The crank pin *f* is connected through a link or pitman *g* with a slide *g*¹ which is mounted on slide rods *g*² so as to have movement in a rectilinear path. A 75 swinging arm *h*, pivoted at *h*¹ on the frame *d*, is connected with the slide *g*¹ through a pin and slot connection indicated at *h*². The arm *h* has an extension *h*⁴ with a reduced portion *i* free to move axially in a part *b*¹ of the holder 80 *b*. By such means the spray head *a* receives motion along the chord of the arc of the circle entered at *h*¹ but with the axis of the spray cone always radial to the same center, as indicated by broken lines in Fig. 1. As 85 shown in Figure 4 the spray head *a* is mounted upon the part *b*¹ of the carrier *b*, which part is engaged by the reduced portion *i* of the extension *h*⁴ of the arm *h*. This part *b*¹ is secured to a spindle *b*² which swivels freely 90 in the main part *b* of the carrier. The spray head is therefore free to swing in the plane in which it is also reciprocated in a rectilinear path.

It will be understood that the glass or other material to be sprayed is moved forward under the spray at a uniform rate and it has been found that when the spray head is reciprocated as described on the chord of the arc of the circle centered on the pivot of the 100

swinging arm by which the spray head is actuated while the axis of the cone in which the spray is delivered by the spray head is radial to the same center, as accomplished by the support of the spray head on a holder which moves on the rectilinear guide rods and by the pivoted mounting of the spray head on the holder, the coat of spray on the glass or material is of substantially uniform thickness from edge to edge.

10 I claim as my invention:

1. An apparatus for spraying glass, etc. comprising a spray head, means to reciprocate the spray head including a swinging arm, and means to guide the spray head on the chord of the arc centered on the pivot of the swinging arm with its axis radial to the same center, whereby the spray head is reciprocated in a rectilinear path parallel with the plane in which the arm swings.
- 15 2. An apparatus for spraying glass, etc. comprising a spray head, a holder on which the spray head is pivotally mounted, a rectilinear slide rod on which the holder is supported, a swinging arm in operative relation with the holder, and means to oscillate the arm whereby the spray head is reciprocated in a rectilinear path and at the same time is free to swing in the plane of rectilinear movement.
- 20 3. An apparatus for spraying glass, etc. comprising a spray head, a holder on which the spray head is pivotally mounted, a rectilinear slide rod on which the holder is supported, a swinging arm in operative relation with the holder, a crank, and an operative connection between the crank and the swinging arm.
- 25 4. An apparatus for spraying glass, etc. comprising a spray head, a holder on which the spray head is pivotally mounted, a rectilinear slide rod on which the holder is supported, a swinging arm in operative relation with the holder, a second slide rod, a
- 30 45 slide on the last named slide rod, a pin and slot connection between the swinging arm and said slide, and means to reciprocate the slide.

This specification signed this 19th day of July, A. D. 1929.

JOHN HENRY JUERS.
